United States Patent Office.

CARL SCHULTZ AND THOMAS WARKER, OF NEW YORK, N. Y.

Design No. 3,017, dated May 5, 1868.

DESIGN FOR A TRADE-MARK.

The Schedule referred to in these Letters Patent and making part of the same.

TO ALL WHOM IT MAY CONCERN:

Be it known that we, CHARLES SCHULTZ and THOMAS WARKER, of the city, county, and State of New York, have invented a new and ornamental Design for a Trade-Mark; and we do hereby declare the following to be a full, clear, and exact description thereof, reference being had to the accompanying drawing, forming part of this specification.

The drawing represents a face view of this design.

This design consists in a cottage, provided with a series of arches, with a sectional roof, in combination with the letters C P on one side, and the letters M S on the opposite side, in such a manner that a new and ornamental trade-mark is produced, which is readily distinguished, and which gives to the article on which it is placed a peculiar appearance.

A represents our trade-mark, which consists of a cottage, *a*, placed between the letters C P and M S, as shown.

Having thus described our invention, what we claim as new, and desire to secure by Letters Patent, is—
The design for a trade-mark, as shown and described.

CARL SCHULTZ,
THOMAS WARKER.
